UNITED STATES PATENT OFFICE.

AUGUST E. R. BLOMQUIST, OF CLEVELAND HEIGHTS, OHIO.

VIBRATING MACHINE.

Application filed April 10, 1925. Serial No. 22,202.

This invention relates to a vibrating machine that is used for massaging parts of the human body.

The objects of the invention are to provide a machine of the aforesaid class which stands on the floor and is conveniently adjustable to different positions so that various parts and members of the human body may be easily and comfortably presented to it for treatment; to provide a machine of the aforesaid character which administers a treatment identical with that known as the "Swedish" massage; to provide a machine of the foregoing nature that is capable of producing different speeds of the applicator to the end that the vigorousness of the "manipulation" or treatment may be varied according to requirements; and to provide a machine of the class above mentioned that is highly efficient, is very substantial, and is very durable.

The foregoing objects, with other and more specific ones hereinafter appearing, are attained in the construction illustrated in the accompanying drawings wherein Fig. 1 is a sectional side elevation of the machine; Fig. 2 is a rear end elevation; Fig. 3 is an enlarged transverse section through the upper portion of the machine, the plane of section being taken substantially on the line 3—3 of Fig. 1; Fig. 4 is a section on the line 4—4 of Fig. 1; and Fig. 5 is a sectional detail of the gear shift fork.

The machine consists of a comparatively heavy downwardly diverging base 1 that may be equipped with pads 2 of rubber or the like; and secured to the base, as by a central bolt 3, is a yoke 4. A gear casing 5 is supported within the upper end of the yoke 4 by trunnions 6 and 7 that are journaled, respectively, within the transverse bores of bosses 8 and 9 wherewith the upper ends of the branches of the yoke 4 are provided, the inner ends of the trunnions being reduced, as shown at 10, and inserted into sockets 11 in the sides of the gear casing 5 and secured therein by pins 12. The trunnion 7 is extended a considerable distance beyond the adjacent branch of the yoke 4 and is reduced in diameter and threaded, as shown at 15, and the hub of a hand wheel 16 is screwed upon the threaded extension of the trunnion. An anti-friction thrust bearing 17 is interposed between the inner end of the hand wheel hub and a shoulder 18 that is formed by the end wall of a shallow re-

cess in the outer face of the boss 9 and which recess accommodates the bearing 17. By means of the hand wheel 16, the casing 5 may be clamped in any angular position 60 with respect to the yoke 4 within the range of its pivotal movement. The outward movement of the hand wheel 16 is stopped by a washer 19 that is held to the end of the trunnion extension by a screw 20.

A housing 25 occupies the casing 5 and the same is composed of circular end walls 26 and 27 and a curved wall 28 which connects the end walls (see Fig. 3). The end wall 26 closes the rear end of the casing 5, while the 70 wall 27 occupies a cylindrical seat 29 that extends circumferentially about the interior of the casing. Screws 30 are extended through the peripheral portion of the end wall 26 and into the end of the casing 5 and 75 serve to hold the housing in place. The housing is extended rearwardly beyond the wall 26 in the form of a shell 31 into which the forward end of the casing of a motor 32 fits. The motor is held to the shell 31 by 80 screws 33 which have their inner ends threaded into internal lugs 34 of the shell.

The motor shaft 35 extends to the forward part of the housing 25 where it is journaled within a standard 36 that rises from the bottom of the housing. Intermediate its ends the shaft 35 bears in a bushing 37 and at its rear end said bushing is enlarged and recessed to receive a packing washer 38 that is held within the recess by a plate 39. The 90 motor shaft 35 has secured to it gears 40, 41 and 42 which are adapted, respectively, to mesh with gears 43, 44 and 45 that are carried by a sleeve 46 slidably mounted upon a counter shaft 47 that is journaled at its opposite ends in the end walls 26 and 27. The latter gears are keyed to the sleeve 46 and at the same time held against rotation with respect to the shaft 47 by keys 48 that extend through keyways in the sleeve and enter a 100 spline 49 in the shaft. The shaft 47 is equipped with a collar 50 at its rear end and at its forward end carries a disk 51 having a crank pin 51 to which is connected, through a suitable anti-friction bearing 53, a head 105 54 that is fastened to the rear end of a shaft 55.

This shaft is supported adjacent its forward end in a bearing 56 which is of the same nature as the bearing 53, the present 110 bearing being fitted within the forward end of an extension 57 of the gear casing 5. The

shaft 55 is held from rotating by a pin 60 that occupies a notch 61 in a transverse wall 62 of the extension 57. A sleeve nut 65 is threaded onto the forward end of the extension 57 and clamps the flanged inner end of a shell 66, and the outer member of the anti-friction bearing 56, in place. A cap 67 is secured, as by nuts 68, to the protruding end of the shaft 55 and carries a packing ring 69 that bears against the spherical forward end of the shell 66. The inner member of the anti-friction bearing 56 is held in place through a spacer 70 that is interposed between said member and the cap 67. A packing element 71 fills the recessed forward end of the extension 57 inwardly of the anti-friction bearing 56 and an annular plate 72 separates said bearing from the packing element.

From the manner above described of mounting the shaft 55 it will be readily seen that when the counter shaft 47 is rotated it will impart a wobbling action to the shaft 55 the latter shaft being held against rotation by the pin 60, the bearings 53 and 56 being of such nature as will permit wobbling of the shaft 55.

Secured, as by a clamping head 75, to the forward extremity of the shaft 55 is a bell shaped applicator 76 which is constructed of rubber or the like. Different kinds of applicators may be substituted for the one shown, depending upon the purpose for which the same is to be used. The one illustrated may be employed for treating the chest, the abdomen, the arms, leg and shoulders. For the spine, a different type of applicator may be employed, and the same is true with respect to the lower limbs and feet, in the latter case stirrup or socket-like devices being employed and in which the foot may rest. These constitute no part of the present invention and illustration is therefore deemed unnecessary.

It may be explained that in the use of the machine, the casing 5 is clamped to the yoke 4 by means of the hand wheel 16 in the position which best adapts the machine to the particular part of the body that is to be treated. When operating on the chest, shoulders, or arms, the front end of the casing 5 is inclined upwardly so that the person, standing on the floor on which the machine rests, may lean against the applicator. The applicator is placed about waist high for abdominal or hip treatments. It is lowered to a point adjacent the floor for treatments of the lower limbs, as well as when using the stirrup like applicator in which the foot rests, the person sitting while taking such treatments. Normally, with the hand wheel 16 relaxed, the forward end of the casing 5 is held elevated by the weight of the motor 31. A bumper 77 of rubber or the like is set within the crotch of the yoke 4 to re-

ceive the motor as it swings downwardly thereby to prevent the metal parts from striking together.

It will be understood from the construction already described that the applicator 70 travels in an orbital path of comparatively small radius; and it may be explained that its movement is at a comparatively high rate of speed. This speed, however, is changeable by the shifting of the gears previously referred to by means which I shall now describe.

Fitted within a circular opening 80 in the top of the gear casing 5 is the reduced inner end of a member 81 that is secured to the casing by screws 82. Journaled within a central aperture of the member 81 is a shaft 83 to the reduced upper end of which is fastened, as by a pin 84, a handle 85. A disk 86 is secured to the reduced lower end of the shaft 83 and the same is adapted to be rotated by the handle 85. The disk 86 is restrained in three different positions with respect to the member 81 by a ball 87 that occupies a recess 88 in the member 81 and is depressed by a spring 89 that is confined between the ball and the top wall of the recess, the ball 87 being adapted to occupy any one of three depressions 90 in the disk 86. Rotatably connected to the disk 86 by means of a pin 91 (Fig. 5) is a fork 92 which embraces the top portion of the gear 43 and through which the gear is free to move during its rotation. By rotating the handle 85, the sleeve carrying the gears 43, 44 and 45 may be slid, through the intervention of the fork 92 and the gear 43, along the shaft 47 so as to disengage gear 43 from the gear 40 and engage either gear 44 or 45 with the gears 41 or 42, respectively. Obviously, the base 93 of the handle 85 and the peripheral portion of the member 81 may bear marks co-operating to indicate the gear positions. In order to quickly and conveniently align the teeth of the gears as they are being thrown into mesh by the handle 85, the gears on the motor shaft 35 may be rotated by means of a hand wheel 95 that is secured to the rear end of the motor shaft. A fan 96 is applied to the motor shaft inside the shell 31, and said shell is provided with ventilating openings 97. A quantity of oil may be contained within the casing 5 and flow from end to end thereof as the casing is tilted so as to lubricate all bearings within the casing, the oil being prevented from flowing to the motor compartment by the packing washer 38 and from leaking through the front of the extension 57 by the packing element 71.

Having thus described my invention, what I claim is:

1. A vibrating machine comprising a support, an elongated casing pivoted to the support on a substantially horizontal axis, an applicator situated beyond the forward end

of the casing, a motor rigidly secured to and located beyond the rear end of the casing, variable speed driving connections between the motor and the applicator and housed within the casing, and means extending through an opening in the wall of the casing for manipulating the variable speed driving connections.

2. A vibrating machine comprising a support, an elongated casing converging toward its forward end and pivoted adjacent its rear end to the support on a substantially horizontal axis, a shaft swiveled adjacent its forward end in the corresponding end 75 of said casing, a crank rotatably supported within the casing and to which the rear end of the shaft is connected, means for holding the shaft against rotation, a motor rigidly secured to and located beyond the rear end 20 of the casing, variable speed driving connections between the motor and the crank and housed within the casing, means extending through an opening in the wall of the casing for manipulating the variable 25 speed driving connections, and an applicator carried by the forward end of said shaft.

3. A vibrating machine comprising a support, an elongated casing open at its rear end and pivoted to said support, a shaft swiveled adjacent its forward end in the corresponding end of the casing, a housing occupying the rear portion of the casing and incorporating a part that serves 35 as a closure for the rear end of the casing, a motor supported by and rearwardly of the housing, a crank supported by and forwardly of the housing within the casing, driving connections between the motor and the crank and contained within said housing, a shaft swiveled adjacent its forward end within the corresponding end of the casing and having its rear end connected to the crank, and an applicator carried by the 40 forward end of the shaft.

4. A vibrating machine comprising a support, an elongated casing open at its rear end and pivoted to the support on a substantially horizontal axis, a shaft swiveled 45 adjacent its forward end in the corresponding end of the casing, a housing occupying the rear portion of the casing and incorporating a part that serves as a closure for the rear end of the casing, a motor supported by and rearwardly of the housing, a crank supported by and forwardly of the housing within the casing, variable speed driving 50 connections between the motor and the crank and contained within said housing, there being an opening in the wall of the casing, means extended through said opening for manipulating said variable speed driving 55 connections, a shaft swiveled adjacent its forward end within the corresponding end of the casing and having its rear end con-

nected to the crank, and an applicator carried by the forward end of the shaft.

5. A vibrating machine comprising a support, an elongated casing that is open at its rear end and is pivoted to the support on a substantially horizontal axis, a shaft that is swiveled adjacent its forward end in the corresponding end of the casing, a housing that is adapted to be inserted within the casing through the rear open end 75 thereof and incorporating a part serving to close said open end of the casing, a motor supported by and rearwardly of the housing, a crank sustained by the housing forwardly thereof and within the casing, 80 means through which said crank and the rear end of the aforesaid shaft assume driving connection when either the housing or the shaft is inserted within the casing, variable speed driving connections between the 85 motor and the crank and supported within the housing, the casing having an opening in its wall, means adapted to be extended through said opening and thereupon assume operative connection with said variable speed driving connections, said means incorporating a part which serves to close said opening, and an applicator carried by the 90 forward end of the aforesaid shaft.

6. A vibrating machine comprising a base, a yoke rising from the base, an elongated casing having opposed trunnions adjacent its rear end that are journaled within the opposed branches of the yoke, the rear portion of the casing being enlarged and open at its rear end, a housing occupying the enlarged portion of the casing and incorporating a wall which constitutes a closure for the rear open end of the casing, a motor supported by and rearwardly of the housing, a crank supported by and forwardly of the housing within the casing, driving connections between the motor and the crank, a shaft occupying the forward portion of the casing and swiveled adjacent its forward end to the corresponding end of the casing, the rear end of said shaft having operative connection with the crank, means for holding the shaft against rotation, and an applicator carried by the forward end of the shaft.

7. A vibrating machine comprising a base, a yoke rising from the base, an elongated casing having opposed trunnions adjacent its rear end that are journaled within the opposed branches of the yoke, the rear portion of the casing being enlarged and open at its rear end, a housing occupying the enlarged portion of the casing and incorporating a wall which constitutes a closure for the rear open end of the casing, a motor supported by and rearwardly of the housing, a crank supported by and forwardly of the housing within the casing, variable speed driving connections between the motor and the crank, a shaft occupying the forward portion of the casing and

tion of the casing and swiveled adjacent its forward end in the corresponding end of the casing, the rear end of said shaft having operative connection with the crank, means 5 for holding the shaft against rotation, there being an opening in the top wall of the casing, means occupying said opening and through which the variable speed driving connections are adapted to be manipulated 10 from outside the casing, and an applicator carried by the forward end of the aforesaid shaft.

8. A vibrating machine comprising a base, a yoke rising from the base, an elongated 15 casing having opposed trunnions adjacent its rear end that are journaled within the opposed branches of the yoke, the rear portion of the casing being cylindrical and open at its rear end, the walls of the casing converging gradually forwardly from said cylindrical portion, cylindrical seats spaced apart 20 longitudinally of the casing within the rear portion thereof, a housing occupying the rear portion of the casing and having portions fitting within the aforesaid cylindrical seats, the housing being designed to provide 25 a closure for the rear end of the casing, a motor supported by and rearwardly of the housing, a crank supported by and forwardly of the housing within the casing, a shaft 30 swiveled adjacent its forward end in the corresponding end of the casing and having its rear end connected to said crank, an applicator carried by the forward end of said shaft, variable speed drive connections between 35 the motor and the crank and supported within said housing.

9. A vibrating machine comprising a base, a yoke rising from the base, an elongated 40 casing having opposed trunnions adjacent its rear end that are journaled within the opposed branches of the yoke, the rear portion of the casing being cylindrical and open at its rear end, the walls of the casing converging gradually forwardly from said cylindrical portion, cylindrical seats spaced apart 45 longitudinally of the casing within the rear portion thereof, a housing occupying the rear portion of the casing and having portions fitting within the aforesaid cylindrical seats, the housing being designed to provide 50 a closure for the rear end of the casing, a motor supported by and rearwardly of the housing, a crank supported by and forwardly of the housing within the casing, a shaft 55 swiveled adjacent its forward end in the corresponding end of the casing and having its rear end connected to said crank, an applicator carried by the forward end of said shaft, variable speed drive connections between 60 the motor and the crank and supported within the housing, the wall of the casing having an opening situated between the aforesaid cylindrical seats, and means occupying said opening and through which said variable speed driving connections may be manipulated from the outside of the casing.

In testimony whereof, I hereunto affix my signature.

AUGUST E. R. BLOMQUIST.
